CLAIM

The ornamental design for an article of flatware, as shown and described.

DESCRIPTION

FIG. 1 is a front elevation view of an article of flatware showing my new design as embodied in a teaspoon;

FIG. 2 is a side elevation view of the teaspoon;

FIG. 3 is a rear elevation view of the teaspoon;

FIG. 4 is a front elevation view of an article of flatware showing my new design as embodied in a seafood fork;

FIG. 5 is a side elevation view of the seafood fork;

FIG. 6 is a rear elevation view of the seafood fork;

FIG. 7 is a front elevation view of an article of flatware showing my new design as embodied in a fork;

FIG. 8 is a side elevation view of the fork;

FIG. 9 is a rear elevation view of the fork;

FIG. 10 is a front elevation view of an article of flatware showing my new design as embodied in a serving fork;

FIG. 11 is a side elevation view of the serving fork;

FIG. 12 is a rear elevation view of the serving fork;

FIG. 13 is a front elevation view of an article of flatware showing my new design as embodied in a salad fork;

FIG. 14 is a side elevation view of the salad fork;

FIG. 15 is a rear elevation view of the salad fork;

The distinguishing feature of my new design for an article of flatware resides in the handle configuration.

FIG. 3. FIG. 2. FIG. 1.

FIG. 15.   FIG. 13.
FIG. 14.

FIG. 6.   FIG. 5.   FIG. 4.

FIG. 9. FIG.8. FIG. 7.

FIG. 11. FIG. 10. FIG. 12.
